OTHER PUBLICATIONS

Townsend Engineering Company, "no load blade". Date: Apr. 28. 1999.

* cited by examiner

Primary Examiner—Stella M. Reid
Assistant Examiner—Mark A Goodwin(57) **CLAIM**

I claim the ornamental design for a cutting blade sleeve, as shown and described.

DESCRIPTION

FIG. 1 is a perspective view of the cutting blade sleeve showing the new design;

FIG. 2 is a top plan view thereof; and,

FIG. 3 is a bottom plan view thereof.

The small dashed broken lines represent perforations and the large broken line showing of a cutting blade is included for the purpose of illustrating environmental structure and forms no part of the claimed design.
